UNITED STATES PATENT OFFICE.

FLOYD J. METZGER, OF NEW YORK, N. Y., ASSIGNOR TO AIR REDUCTION COMPANY, INCORPORATED, A CORPORATION OF NEW YORK.

ILLUMINATED INSTRUMENT.

Application filed May 23, 1922. Serial No. 562,939.

To all whom it may concern:

Be it known that I, FLOYD J. METZGER, a citizen of the United States, residing at New York, in the county of New York, 5
5 State of New York, have invented certain new and useful Improvements in Illuminated Instruments; and I do hereby declare the following to be a full, clear, and exact 10 description of the invention, such as will 10 enable others skilled in the art to which it appertains to make and use the same.

This invention relates to gauges or measuring instruments, and particularly to the illumination of devices of this character 15 whereby the same may be rendered visible in the dark.

An object of the invention is to provide a simple and inexpensive illuminated temperature or pressure gauge, and particularly the 20 provision of means whereby the illumination may be obtained with a minimum expenditure of electric current.

A special application of the invention is in thermometers such as are employed to indicate temperature of the circulating liquid 25 in cooling systems for internal combustion engines. It is to be observed, however, that the invention is not limited to such use, being generally applicable to thermometers, 30 barometers and other measuring instruments.

The invention depends upon the use of a gaseous medium of high electrical conductivity which may be caused to glow by an 35 electrical discharge resulting from the passage of a high tension current through the gas. Any suitable gas may be employed, although gases such as neon and helium are preferred because of their low dielectric 40 strength which permits of the illumination with an extremely small amount of current. It is to be understood, however, that vacuum tubes containing air, carbon dioxide, nitrogen, argon or other gases under reduced 45 pressure may be employed, provided sufficient current is available to ensure the proper illumination.

The high tension current may be obtained 50 from any suitable source as, for example, an ordinary induction coil, the primary circuit of which is supplied with current from a suitable source. The high tension current

generated by the induction coil may be delivered directly to a glow vessel containing the gas. In the special application of 55 my invention the high tension current is derived from the ignition system of the engine, and I have discovered that sufficient current for the purpose may be supplied from the ignition system. The amount of 60 current supplied to the glow vessel may be regulated by the interposition of a properly proportioned choke coil or condenser between a high tension conductor of the ignition system and the illuminating device, and 65 the surplus energy usually present in ignition systems may be utilized without detrimental effect upon the operation of the engine. In the preferred embodiment of the invention the condenser is connected to a 70 terminal of one of the spark plugs and of course several condensers may be employed and connected to the several spark plugs so that a more or less continuous illumination 75 is effected. If a single spark plug is connected to the illuminating device a flash will be observed at each instant when the particular plug is supplied with current.

In the accompanying drawing I have illustrated the preferred embodiments of the 80 invention, it being understood, however, that the details may be varied and that the drawing is illustrative merely. In the drawing,

Fig. 1 is an elevation partially in section illustrating the temperature gauge adapted 85 for use in connection with the cooling system of an internal combustion engine;

Fig. 2 is a transverse section through the structure illustrated in Fig. 1;

Fig. 3 is a diagrammatic illustration of 90 an electrical circuit embodying the device;

Fig. 4 is a similar illustration of another electrical circuit; and

Figs. 5 and 6 are details in section of different forms of the illuminating device. 95

Referring to the drawing, 5 indicates a frame which may be circular in form and which is adapted to be supported on the usual cap 6 which closes the radiator filling spout 7 of the cooling system. The frame 5 terminates in a housing 8 which passes through an opening in the cap 6 and is secured thereto by a nut 9, thus rigidly holding the device in assembled relation 100

with the cap. A thermometer 10 is supported in the frame 5, the lower or bulb end (not shown) of the thermometer being preferably embedded in a suitable cement 5 within the housing 8. The thermometer is of the usual type containing mercury or heat-sensitive liquids such as xylol or alcohol which ascend the capillary bore 11 of the thermometer. A scale 12 is supported in 10 the frame 5 behind the thermometer 10 and may bear suitable graduated marks whereby the thermometer readings are interpreted. The scale 12 is preferably provided with an opening 13 near the upper end of the thermometer which indicates the danger zone.

A shell 14 is supported on the frame 5 at the rear thereof and behind the opening 13 in the scale 12. Within the shell 14 I provide a tube 15 of some transparent material such as glass which contains a gaseous medium, preferably neon or helium. The neon or helium may be under reduced pressure, preferably from 10 mm. to one-half atmosphere, and if a vacuum tube containing 25 air, carbon dioxide, nitrogen, argon or other gases is used, the pressure should be considerably lower. The tube 15 is provided at one end with an electrode or mass of metal wool 16 which is connected by an insulated 30 conductor 17 extending preferably about the inner periphery of the frame 5 and supplied with high tension current from a suitable source. The other end of the tube 15 is also provided with an electrode or mass of metal 35 wool 18 which is connected by a conductor 18' to the shell 14. Metal foil may be employed in place of the metal wool or a coating of metal may be deposited upon the end of the tube 15. The metal wool, foil or 40 coating at the end opposite the electrode is preferably grounded, but if a sufficient surface is provided the dispersive effect will result in the completion of the circuit even though a direct connection through the 45 frame is not provided.

The current may be supplied, for example, from an induction coil 19, the primary of which is connected by conductors 20 and 21 to a source of current 22. The high tension current generated in the secondary may be delivered through a conductor 23 to the electrode 16 in the tube 15 and is thence dispersed or conveyed to the ground through a conductor 24. The opposite high tension 55 terminal of the coil 19 is connected to the ground by a conductor 25. A circuit closer 60 is disposed in the conductor 20 so that current may be supplied for the purpose of illuminating the thermometer as may be desirable.

In Fig. 4 the diagrammatic illustration shows a circuit adapted for use in connection with the high tension ignition system of an internal combustion engine, this being 65 the preferred embodiment of the invention.

tion. A spark plug 27 having a terminal 28 is connected by a conductor 29 to any suitable source of high tension current. The shell 30 of the spark plug is connected by a conductor 31 to the ground. A conductor 70 32 connects the terminal 28 to a condenser 33 or a choke coil. The conductor 17 connects the condenser to the electrode 16 in the tube 15. The current passing through the tube 15 is dispersed or conveyed to the 75 ground by a conductor 34. This arrangement is particularly well adapted for use in producing the desired illumination. The high tension current is necessarily employed in the ignition system and sufficient 80 current can be supplied therefrom to illuminate the tube without interfering with the operation of the engine. This avoids the necessity of providing a separate source 85 of high tension current.

In Fig. 5 of the drawing a modification of the invention is illustrated in which a tube 35 is disposed in a suitable insulated casing 36 with its ends surrounded by conducting material having a considerable electrical capacity such as metal wool 37. Metal foil or coatings of metal upon the ends of the tube may be employed in place of the metal wool. The conductor 17 is connected to a metallic contact 38 which in turn 90 engages the capacity medium at one end of the casing 36. The other end need not be connected directly to the ground since the dispersive effect is sufficient to ensure operation of the tube.

In Fig. 6 of the drawing another form of the invention is illustrated, in which a tube 39 is provided with an electrode 40 at one end projecting through the wall of the tube into the interior thereof. The tube is surrounded by an insulated casing 42 and the insulated conductor 17 is connected to an electrode 40. The opposite end of the tube is surrounded by a capacity medium such as 100 metal wool, metal foil or a coating of metal.

From the foregoing it will be observed that I have provided an illuminating device which is readily applicable to measuring instruments and which is particularly desirable in illuminating thermometers applied to the cooling systems of internal combustion engines because of the simplicity with which the necessary high tension current may be obtained from the ignition system through the interposition of the condenser 115 or choke coil as hereinbefore described.

Various changes may be made in the details of construction and arrangement of the various parts within the scope of the accompanying claim without departing from the 120 invention or sacrificing any of the advantages thereof.

I claim:

In a temperature indicator for the cooling system of an internal combustion engine 125

provided with sparking terminals, the combination of a temperature-responsive device, a scale behind the device having an opening therein, a casing behind the scale having a corresponding opening, a gas-containing receptacle within the casing and means for electrically connecting the ends of the receptacle respectively to one of the sparking terminals and to the ground, said means including metal wool at the ends of the receptacle.

In testimony whereof I affix my signature.

FLOYD J. METZGER.
